[57] CLAIM

We claim the ornamental design for surface ornamentation for a control panel on a range top, as shown and described.

DESCRIPTION

FIG. 1 is a top view of surface ornamentation for a control panel on a range top, the broken line drawing of a range top is for illustrative purposes only and forms no part of the claimed design;

FIG. 2 is a top view thereof, the surface ornamentation is shown separately for clarity of illustration; and,

FIG. 3 is a top view of a second embodiment thereof, the surface ornamentation is shown separately for clarity of illustration.
